The ornamental design for a trifold pharmaceutical tablet dispenser, as shown and described.

DESCRIPTION

FIG. 1 is a perspective view of a trifold pharmaceutical tablet dispenser showing our new design;
 FIG. 2 is a side elevational view of FIG. 1, the opposite side being a mirror image of the side shown;
 FIG. 3 is a tray-end elevational view of FIG. 1;
 FIG. 4 is a cover-end elevational view of FIG. 1;
 FIG. 5 is a top plan view of FIG. 1;
 FIG. 6 is a bottom plan view of FIG. 1;
 FIG. 7 is a perspective view of the trifold pharmaceutical tablet dispenser with the end-tray folded over the middle-tray;
 FIG. 8 is a side elevational view of FIG. 7, the opposite side being a mirror image of the side shown;
 FIG. 9 is a folded tray-end elevational view of FIG. 7;
 FIG. 10 is a cover-end elevational view of FIG. 7;
 FIG. 11 is a top plan view of FIG. 7;
 FIG. 12 is a bottom plan view of FIG. 7;
 FIG. 13 is a perspective view of the trifold pharmaceutical tablet dispenser with the cover folded over the two tablet trays;
 FIG. 14 is a side elevational view of FIG. 13, the opposite side being a mirror image of the side shown;
 FIG. 15 is a front end elevational view of FIG. 13;
 FIG. 16 is a back end elevational view of FIG. 13;
 FIG. 17 is a top plan view of FIG. 13; and,
 FIG. 18 is a bottom plan view of FIG. 13.
